and L. Browning

UNITED STATES PATENT OFFICE.

FENTON R. BRYDLE, OF JAMAICA, NEW YORK.

SHINGLE.

Application filed April 18, 1925. Serial No. 23,439.

This invention relates generally to shingles of the composition type.

A general object of the invention is to provide a shingle of this general type in which the edge portions exposed to the weather will present impervious surfaces of a stable character resistant to the action of wind and rain. Another object of the invention is to provide improved means for anchoring the lower extremities of the shingles in position.

The invention consists of a shingle having an undeturned corner tab portion cooperating with undeturned edge portions on the portion of the shingle exposed to the weather to provide impervious and relatively thick and substantial edges. The corner tab portion is preferably so formed as to extend laterally under the edges of adjacent shingles although the horizontal edge visible to an observer extends only from edge to edge of the two adjacent underlying shingles.

Other features of the invention will be hereinafter referred to.

In the drawings in which a preferred embodiment of the invention has been selected for illustration,

Figure 1 is a plan view showing in assembled relation a group of shingles embodying the invention.

Figure 2 is a view in cross-section on the line 2-2 of Figure 1.

Figure 3 is a line in cross-section on the line 3-3 of Figure 1.

Figure 4 is a face view of the under side of one of the shingles shown in Figure 1.

Figure 5 is a sectional view of the shingle shown in Figure 4.

Figure 6 is a detailed view showing a portion of a shingle before the edges are folded.

Referring to the drawings for a more detailed description of the invention, the improved shingle 10 herein shown is provided with an undeturned corner tab member 11 having laterally extending corner portions 12 which serve to underlie and provide an anchoring engagement with adjacent shingles 10' over which the shingle 10 is laid in the shingling operation.

In order to provide the lateral extensions 12 in the tab member 11 the tab is initially formed as shown in Figure 6 of the drawing with side edges 13 formed substantially at right angles to the side edges 14 of the body portion of the shingle 10. With this arrangement it will be seen that when the tab

member 11 is folded to the undeturned position the angular or corner portions 12 will assume the form of lateral extensions with relation to the body portion of the tab and will thus provide for the anchoring engagement referred to with the previously laid adjacent shingles. Preferably the extreme downwardly extending corner portion of the tab 11 is removed to provide an edge 15 such as is clearly shown in Figures 4 and 6 of the drawing.

In addition to the undeturned corner portion 11, I provide for the turning under of the downwardly converging edge portions 13 of the lower half portion of the shingle. The purpose of this is to provide an undeturned and accordingly impervious surface for presentation to the weather, it being clear that the new edge portion 16 which is thus provided has the same impervious surface finish that is characteristic of the outer face of the main body portion of the shingle 10. By thus doing away with the raw or cut edge which is characteristic of this general type heretofore known and used, I succeed in doing away with the wear and tear to which such edges are subjected under the action of rain and wind.

In addition to the resistance to weather which is provided by the turned edges 16, a more stable construction in general is provided in that the edge portions of the lower part of the shingle have a double thickness. An additional advantage of this construction resides in the attractive appearance which is presented by the thickened edge lines with the accompanying shadows which contribute substantially to the attractiveness of a roof or wall protected by shingles of this type.

It will be seen that the turned edges 16 are provided only on the downwardly facing edges of the shingle and that the upper edges of the shingles remain in their flat or unturned condition. With this arrangement there is no interlocking of the edge portions 16 with the underlying shingles nor is there need of any such interlocking since an ample anchoring function is provided by the anchoring tab member 11 already referred to.

What I claim is:

1. A flexible shingle of the composition type having an undeturned corner tab member formed with lateral extensions to provide anchoring engagement with adjacent shin-

gles, and the adjacent converging edges of the shingle being undeturned into engagement with the lower surface of the shingle to present impervious surfaces to the 5 weather.

2. In a flexible composition shingle of the individual type, an undeturned corner tab portion formed with lateral extensions to provide anchoring engagement with adjacent 10 shingles, and the adjacent lower edges of the shingle being undeturned into engagement with the lower surface of the shingle to form reinforcing edges.

3. In a flexible composition shingle of the 15 individual type, a corner tab member formed with edges extending substantially at right angles to the adjacent edges of the shingle whereby to provide lateral angular extensions on the tab members, and the adjacent 20 edges of the shingle being underfolded into adhering contact with the lower surface of the shingle to provide reinforced edges and edges impervious to weather.

4. In a flexible composition shingle of the

individual type, a corner tab member formed 25 with edges extending substantially at right angles to the adjacent edges of the shingle whereby when folded to undeturned position said tab edges will be parallel to the edges of the shingle, and said adjacent edges 30 of the shingle being folded under into contact with the lower surface of the shingle, the line of fold of the edge portions being in alinement with said edges of the tab member. 35

5. In a flexible composition shingle of the individual type, and undeturned corner tab member formed with laterally extending corner portions, and the adjacent edges of the shingle being undeturned into contact with 40 the lower surface of the shingle, said folded edge portions being cut away to avoid interference with the corner tab portions, and the line of fold of the edge portions being in alinement with the ends of the line of fold 45 of the corner tab member.

FENTON R. BRYDLE.
